UNITED STATES PATENT OFFICE.

LLOYD L. ROSS, OF DES MOINES, IOWA, ASSIGNOR OF ONE-HALF TO CHARLES H. FENNELL, OF DETROIT, MICHIGAN.

MECHANISM FOR RUBBING AND POLISHING.

Application filed June 6, 1924. Serial No. 718,261.

My invention relates to devices for rubbing and polishing surfaces, such as furniture, automobile bodies and the like.

The object of my invention is to provide a mechanism for sanding, rubbing and polishing, of simple, durable and inexpensive construction, whereby power may be applied for the purpose.

More particularly, it is my object to provide in such a device or mechanism a movable head preferably mounted for rotation and to provide a flexible rubbing element thereon in connection with springs interposed between the head and the rubbing element in such manner that when the rubbing element is pressed against the surface to be rubbed or such surface is pressed against the element, the springs will yieldingly engage the element at a plurality of points for insuring the effective operation of the device on flat and other surfaces.

A further object consists in providing novel means for mounting the polishing element and the springs on the head.

A further purpose of my invention is to provide in connection with such a mechanism suitable means for feeding an abrasive to the rubbing element when desired and for accurately regulating the flow of such abrasive to the rubbing element.

More particularly, in the latter respect, it is my purpose to provide in connection with the rubbing device itself a tank and a tube with means for positively feeding the abrasive from the tank to the tube and with a valve for controlling the flow of abrasive through the tube.

Still another purpose of my invention is to provide in connection with such a feeding mechanism, means for supplying water or other liquid to or with the abrasive.

Another general purpose is to provide a rubbing or polishing mechanism of the kind herein mentioned in which the head is mounted upon a support, which support may be so made as to be adapted to be held in the hand, so that the device may be manually manipulated and moved from place to place. This feature of my invention involves the necessity for using a flexible shaft or its equivalent for operating the head when the device is manually moved about for operation.

With these and other objects in view, my

invention consists in the construction, arrangement and combination of the various parts of my device, whereby the objects contemplated are attained, as hereinafter more fully set forth, pointed out in my claims, and illustrated in the accompanying drawings, in which:

Figure 1 shows an elevation partly in section of the head of a rubbing and polishing machine embodying my invention with connected parts.

Figure 2 shows a side elevation of the head, the rubbing element and springs being shown in positions illustrating the operation of the device.

Figure 3 shows a sectional view taken on the line 3—3 of Figure 1.

Figure 4 shows a sectional view taken on the line 4—4 of Figure 1.

Figure 5 shows a detail, sectional view of the parts of the head ready for assembling.

Figure 6 is a sectional view taken on the line 6—6 of Figure 5.

Figure 7 shows a side elevation of the feeding tank for the abrasive and part of the operating mechanism.

Figure 8 shows a detail view partly in section of the device, part of the tank and operating mechanism being broken away.

Figure 9 is a sectional view taken on the line 9—9 of Figure 8.

Figure 10 is a side elevation of the head; and Figure 11 is an enlarged detail sectional view on the line 11—11 of Figure 10 to illustrate the connection of the rubbing element to the rotatable portion of the head.

Generally speaking, my invention may be illustrated in a rotatable head carrying polishing and rubbing means and a tank and connected parts for supplying abrasive to the head.

I shall first describe the head which might be used under some circumstances without the abrasive feeding means.

I have illustrated the polishing head or instrument in the form adapted for manual manipulation and movement from place to place, but it is obvious that it could be used by mounting it so that the article to be rubbed or polished could be moved into adjusted position with relation to the rubbing element.

The head indicated in the accompanying drawings by the reference numeral 10 has

generally the form of a cylinder having in its upper surface 10^a a cylindrical recess 11 and extending therefrom to its lower surface a reduced internally screw-threaded opening 12. The body of the head 10 at the bottom of the opening 11 is undercut to form an enlarged opening 11^a of greater diameter than the opening 11.

There are arranged in the enlarged portion 10 11^a of the opening 11, what I may call catch walls 64. These walls extend from the wall of the enlarged opening 11^a, as shown for instance in Figure 4, inwardly toward the center of the head 10 and thence in the direction of rotation of the head and substantially paralleling the wall surrounding the enlarged portion 11^a of the opening 11.

A series of for instance four holes 13 is provided, each hole 13 extending from what 20^a I may call the under surface of the head 10 upwardly into the body thereof to the enlarged portion 11^a of the opening 11 between one of the walls 64 and the wall of the portion 11^a.

25 The lower part of the head 10 is tapped and provided with a series of spaced screw holes 14 extending radially inwardly from its outer surface and so arranged as not to register with the holes 13 for receiving screws 30 hereinafter mentioned, which are used for fastening the springs, also hereinafter more fully explained, to the head.

An operating shaft 15 has a screw-threaded end 16 adapted to be screwed into 35 the screw-threaded opening 12, as shown in Figure 1.

The shaft 15 may have a shoulder 17, as shown in Figure 5, for obvious purposes.

The screw-threaded end 16 of the shaft 40 15 is tapped to provide a central screw-threaded opening 18, shown in Figures 1 and 5 to receive the screw 19 hereinafter again referred to.

A rubbing element, which may have a 45 variety of forms, but which should have flexibility is provided.

In the particular form of my invention illustrated herein, I have shown the rubbing element 20, as composed of a couple of layers 50 of carpet-like material, felt, emery cloth, sand paper, or any suitable material.

The rubbing or polishing element 20 may be mounted on the head so as to be yieldingly acted upon by the springs hereinafter described in a great variety of ways.

55 In the illustrated form of my invention, I provide an annular plate 21, having a plurality of upstanding hollow posts or tubes 22, as illustrated for instance in Figure 5, 60 designed to project into the holes 13 in the head 10.

In the particular form of my invention here shown, the plate 21 is placed adjacent to the underside of the rubbing element 20 with the tubes 22 projecting upwardly

through the member 20, as shown for instance in Figure 1, and extending through holes 20^b in the member 20 into the holes 13. The plate 21 is provided with a central hole or opening 23 and the screw 19 is extended 70 through the opening 23 in the plate 21 and through the hole 20^c in the rubbing element 20 and is then screwed into the hole 18 in what may be called the lower part of the shaft 15, as shown in Figure 1. 75

When the parts are assembled to the extent just mentioned, it will be seen that the tubes 22 furnish passages from the outer part of the enlarged portion 11^a of the opening 11 through the lower part of the head 10 and through the rubbing element 20 and the plate 21 to the central undersurface of the rubbing element 20. These passages 22 are used for conducting abrasive to the under or rubbing side 20^a of the rubbing element 20 in 80 the manner hereinafter more fully explained.

In order that yielding pressure may be imposed upon the rubbing element 20 at a plurality of points thereon, so as to yieldingly press the rubbing element against all 85 parts of other than flat surfaces, I provide resilient devices, which may be in the form of a series of flat springs 24 inclined radially downwardly and outwardly from the head 10 to bear against what is the upper surface 90 of the rubbing element 20 when the latter is pressed against the top of a horizontal surface to be rubbed.

These spring arms 24 in the form of the invention here illustrated have at their inner 100 ends upwardly projecting portions 25 standing adjacent to the outer surface of the lower part of the head 10. A holding band 26 is arranged just outside the upright portions 25 of the spring arms 24 and is rigidly locked to the portions 25 and to the head 10 by means of a series of screws 27 screwed into the holes 14 hereinbefore referred to. 105

It will thus be seen that the whole series of upwardly extending portions 25 of the spring arms 24 are firmly held adjacent to the lower part of the head 10 between said head and the fastening band 26 by means of the screws 27 extended through the band 26 and the portions 25 and screwed into the 115 holes 14. (See Figures 1, 4 and 6).

It will also be noted from the foregoing description that when the shaft 15 is rotated, the head 10 will rotate therewith and thus rotate the rubbing element 20 and the resilient devices 24. Thus when the rubbing element 20 is pressed against a surface to be rubbed or the article to be rubbed is pressed against the rubbing element 20 and the shaft 15 is held against longitudinal 120 movement, and is rotated, such surface to be rubbed will be frictionally engaged and rubbed or polished by the rubbing element 20, and the resilient devices 24 yieldingly engaging the rubbing element 20 at a va- 125

riety of points will make it possible to use the element 20 for rubbing an uneven as well as a flat surface.

This structure is peculiarly adapted for 5 use in sanding, rubbing and polishing the surfaces of "period" furniture, automobile bodies, which have many curved portions, and the like. It is, of course, also adapted to be used in rubbing and polishing floors, 10 counters, cedar chests, bookcases, pianos and a great variety of other articles and surfaces.

For convenience in holding the shaft 15 in the hand, there is loosely mounted on 15 the shaft a tubular sleeve 28 on which adjacent to the head 10 is a hand guard 29, having a central disc-shaped portion 30 adapted to bear against the upper surface of the head 10, so that the head 10 rotates 20 adjacent to said portion 30. It should perhaps be mentioned that the hand guard 29 is somewhat bell-shaped with a back curved outer portion and that the shape and size of the hand guard 29 is such that when the 25 thickness of the pad 20 is taken into consideration, the plate 21 can never be pressed to engage the surface to be rubbed where that surface is either flat or concave. In other words when the parts are in the position 30 shown in Figure 1, the lowermost part of the hand guard pressing against the pad 20 would hold that pad with its lower surface in a plane below the level of the plate 21 in the assembled device. This is of some 35 importance in that the hand guard 29 serves a double purpose as a hand guard and also as a means for preventing the pressing of the springs and the pad 20 into such shape as to cause the plate 21 to engage the surface 40 to be rubbed.

The shaft 15 may be connected with any suitable source of power for thus imparting rotation to the head 10, but as here illustrated, I have shown the shaft 15 connected 45 as at 31 with a link 32 of a flexible shaft structure 33.

It will thus be seen that the sleeve 28 can be grasped and when the flexible shaft structure is connected with a source of power, the rubbing mechanism may be moved 50 freely from place to place for finishing any desired surface.

What I have called the under-surface of the rubbing element 20 may be dipped into 55 a mixture of an abrasive and water or oil and then applied to the surface to be rubbed and rapidly rotated.

I prefer, however, to supply abrasive to the under surface of the rubbing element 20 60 preferably near the central part thereof in the manner now to be more fully explained.

Suitably supported in any proper way is a supply tank 34 for abrasive. This may be supported upon a platform 35, which in turn

is held by hangers 36 and rollers 37 from 65 a track or the like 38.

The tank 34 preferably has a tapered lower portion 34^a from which there extends downwardly a feed pipe or the like 39 communicating with and extending away from 70 which are one or more tubes 40, for example on opposite sides thereof.

A water or liquid supply tube 41 communicates with the lower end of the feed pipe 39. A valve 42 is provided for controlling the flow of liquid from the pipe 41 into the feed pipe 39, as shown in Figure 8. Valves 43 are arranged to control the flow from the feed pipe 39 to the tubes 40. 75

Branch pipes 44 connect the pipe or hose 41 at points beyond the valve 42 with relation to the feed pipe 39 directly with the tubes 40, as shown in Figure 9. Valves 45 control the flow of liquid from the pipe or 80 hose 41 to the tubes 40.

Supported on the platform 35 is a motor or source of power 46, having the driving shaft 47.

Journaled in suitable bearings, as at 48 90 and 49, is an upright driven shaft 50, which is operatively connected as at 51 with the flexible shaft structure 33, already mentioned.

A shaft 52 is journaled in the member 53 95 at the upper end of the tank 34 and extends downwardly through the tank and into the feed pipe 39, having its lower end journaled, as at 54 (see Figure 8).

On the shaft 52 in the feed pipe 39 is a 100 spiral worm or the like 55 for agitating pumice stone or other abrasive received in the tank 34.

On the shaft 52 is fixed a member 56 from which stirring or agitating arms 57 project 105 outwardly into the tank 34. On the shaft 52 above the tank 34 is a belt pulley 58 aligned with a belt pulley 59 on the shaft 50. A belt 60 travels on the pulleys 58 and 59 for imparting rotation from the shaft 50 to 110 the shaft 52 and thereby operating the agitator arms 57 and the worm 55.

It may be said in this connection that the worm 55 does not entirely and snugly fit the feed pipe 39, but that there is some clearance 115 between it and the interior of that pipe.

The tubes 40 are connected with flexible tubes 61, which extend to and communicate with small pipes or tubes 62 arranged adjacent to and supported on the sleeve 28 and 120 having the controlling valves 63.

The tubes 62, as shown in Figures 1 and 8, extend downwardly through the disc-shaped portion 30 of the guard 29 into the opening 11 down to and projecting into the 125 enlarged portion 11^a thereof.

The lower or discharge ends of the tubes 62 are arranged opening radially outwardly,

as illustrated for instance in Figure 1, so as to discharge under the overhanging flange formed above the outer portion of the enlarged part 11^a of the opening 11.

5 It will be noted that the tubes 62 are stationary and connected with the sleeve 28 and guard 29.

The purpose of the catch walls 64 will now be explained.

10 It will be seen that abrasive and liquid discharged from the tubes 62 will pass into the outer portion 11^a of the hole or opening 11.

15 Centrifugal force will tend to cause the liquid and abrasive to travel to the outside, but in any event the inertia of the material will result in its being caught by the walls 64, so that it will travel to the open upper ends of the tubes 22 and thence through the tubes 22, being driven by the force of the additional following material, and being thus fed to what I have for convenience called the underside of the rubbing element 20 near the central portion thereof.

20 25 I find that the abrasive thus fed to the underside of the rubbing element will be properly distributed as the machine is moved about on the surface being rubbed or polished.

30 35 I will now describe somewhat in sequence the operation of my improved machine.

The finely divided abrasive, such as pumice stone, rotten stone, alundum, sand or others suitable for any desired purpose, may be placed in the tank 34.

It is, of course, understood that the hose or pipe 41 is connected with a suitable source of water or other liquid supply.

40 45 It will be understood that the parts are assembled as hereinbefore explained.

Ordinarily one tube 61 will supply all the abrasive and liquid necessary for efficient operation; the other furnishes, as it were, a "spare."

45 50 The water and liquid are mixed in the tank 34 before any work is started.

Assuming then that it is desired to use the mechanism for rubbing operations and to supply the abrasive through one of the tubes 61, the appropriate valves 63 and 43 are opened and all the other valves are closed. The motor is turned on and the abrasive will flow from the tank, being agitated by the members 57 and 55, through the feed pipe 39, the appropriate tube 40, the flexible tube 61, the appropriate tube 62 to the rotating head, where it travels outside the catch walls 64 to and through the tubes 22 to the rubbing element 20.

60 65 The rubbing element 20 is rotated at a speed appropriate for the work to be done.

The rubbing element 20 may be pressed against the work with whatever pressure is desired for the purpose, and the flow of abrasive can be readily regulated by means

of the valves 63 and 43, so as to feed just the right amount for the purpose.

As a rubbing element 20 is applied to the surface to be polished or finished, the springs 24 will cause the element 20 to engage every part of the surface to be finished, even though that surface is not flat. A curved wall or surface can be properly finished with a tool of this kind.

In case, one tube 61 should become clogged, 75 the operation of the tool can be continued almost instantaneously by opening the valves for feeding abrasive through the other tube 61 and by opening the proper valve 45 and closing the proper valve 43. The clogged 80 tubes can be readily flushed with water or other liquid.

Furthermore, it is readily seen that if it should be desired to mix more water with the abrasive in the rotary head, this can be 85 done by opening the other valve 45 for permitting the flow of any desired amount of water or other liquid directly to the rotary head and thence to the rubbing element.

I have found by actual experience that 90 with a rotating rubbing element of the kind herein described with a plurality of resiliently pressed areas or parts, I can finish a given area or surface in a substantially 95 quicker time than can be done by hand and a finer, smoother and more uniform finish can be obtained.

The workman with a little experience can accurately regulate the flow of abrasive and also regulate the pressure on the rubbing 100 element so as to accurately and artistically secure the desired finish.

It will be understood that some changes may be made in the details of construction and the arrangement of the 105 parts of my improved device, and that the present showing is intended to be illustrative, and it is my intention to cover by my claims, any modified forms of structure or use of mechanical equivalents, which may 110 be reasonably included within their scope.

I claim as my invention:

1. In a device of the class described, a rotary head, a flexible rubbing element secured to said head, yielding devices supported by said head and pressing against said rubbing element for substantial distances radially outwardly from the head and normally holding the rubbing element in the shape of a truncated cone.

2. In a device of the class described, a rotatable head, a rubbing element secured thereto and extending radially therebeyond a plurality of flat springs secured to said head and extending away therefrom adjacent to said rubbing element and normally holding the rubbing element in the shape of a truncated cone.

3. In a device of the class described, a rotary head, a flexible rubbing element

- secured to said head, yielding devices supported by said head and pressing against said rubbing element for substantial distances radially outwardly from the head and
- 5 normally holding the rubbing element in the shape of a truncated cone, and a hand guard supported adjacent to said head and receiving said head and serving as a means for limiting the movement of the rubbing
- 10 element in one direction.
4. In a device of the class described, a rotary head, a substantially cone-shaped rubbing element, a plurality of yielding devices supported by the head and projecting
- 15 therefrom adjacent to one surface of the rubbing element, said head having an annular channel, passages extending from the channel to the rubbing side of the rubbing element, means for discharging abrasive and
- 20 liquid into said channel and a wall adjacent each passage for directing such abrasive and liquid into said passages.
5. In a device of the class described, a rotary head, a substantially cone-shaped rubbing element, a plate adjacent to one surface of the rubbing element for securing the element to the head, a plurality of yielding devices supported by the head and projecting
- 25 therefrom adjacent to the other surface of the rubbing element, and shaped to normally hold the rubbing element in the form of a truncated cone, said plate having tubes open at both ends and extending through the rubbing element and into said head, means
- 30 for discharging abrasive and liquid into said head and a deflector arranged adjacent the end of each tube for causing such abrasive and liquid to enter the tubes.
6. In a device of the class described, a
- 35 tubular sleeve, a shaft rotatable therein, a head secured to said shaft, a substantially cone-shaped rubbing element having one surface secured to said head, a plurality of yielding devices supported by the head and
- 40 projecting therefrom adjacent to the other surface of the rubbing element, a guard member secured to said tubular sleeve for limiting the movement of the rubbing element in one direction, means for discharging abrasive and liquid into said head and
- 45 means operative due to the rotation of the
- head for collecting such abrasive and liquid and conducting it to the rubbing element, said means comprising conducting tubes and deflector walls.
- 55
7. In a device of the class described, a head, a shaft having a screw-threaded connection with said head, a flexible rubbing element, means for securing said flexible rubbing element to said head, comprising
- 60 a plate and a screw extended through said plate and said rubbing element and having a screw-threaded connection with said shaft, means extending into the rubbing element and the head for holding them against
- 65 relative rotation, resilient members supported on said head for engaging said rubbing element in a plurality of substantially radial lines, and an inverted cup-shaped hand guard on said head receiving
- 70 the head and serving as a limiting means for the movement of the flexible rubbing element in one direction.
8. In a device of the class described, a head having at one end a cylindrical opening provided with an enlarged portion at
- 75 its inner part, a flexible rubbing element adjacent to the other side of said head, a plate adjacent to the rubbing element, means for fastening the rubbing element and the
- 80 plate together, said head having a tubular member projecting through said rubbing element and communicating with the enlarged portion of said cylindrical opening,
- 85 and yielding devices supported by said head for engaging said rubbing element.
9. In a device of the class described, a head having at one end a cylindrical opening provided with an enlarged portion at
- 90 its inner part, a flexible rubbing element adjacent to the other side of said head, a plate adjacent to the rubbing element, means for fastening the rubbing element and the
- 95 plate together, said head having a tubular member projecting through said rubbing element and communicating with the enlarged portion of said cylindrical opening,
- 100 yielding devices supported by said head for engaging said rubbing element, and means for supplying abrasive to said opening.

Des Moines, Iowa, May 21, 1924.

LLOYD L. ROSS.
